UNITED STATES PATENT OFFICE.

JAMES WHITELAW, OF ST. LOUIS, MISSOURI, AND GEORGE T. MAY, JR., OF CHICAGO,
ILLINOIS.

SEWING-MACHINE LOOPER.

1,347,313.

Specification of Letters Patent. Patented July 20, 1920.

Application filed April 17, 1919. Serial No. 290,763.

To all whom it may concern:

Be it known that we, JAMES WHITELAW and GEORGE T. MAY, Jr., citizens of the United States, residing at the city of St. Louis, State of Missouri, and Chicago, in the county of Cook and State of Illinois, respectively, have invented certain new and useful Improvements in Sewing-Machine Loopers, of which the following is a specification.

Our invention relates to six-way loopers for chain-stitch sewing machines, more particularly for blind-stitch machines.

Its general object is to provide a simple, efficient looper mechanism capable of operation at high speed and with greatest accuracy, and having excellent durability. The features of construction and combinations of parts constituting our invention are hereinafter more fully described and set forth in the claims, and the advantages thereof will be apparent from the following description.

In the drawings wherein we have illustrated a single embodiment of our invention, Figure 1 is a front view of the looper in assembled relation to suitable parts of a blind-stitch sewing machine of the chain-stitch type; Fig. 2 is an enlarged detail of a cam-operated lever element; Fig. 3 is an end elevation of the machine shown in Fig. 1; Fig. 4 is a vertical section on line 4-4 of Fig. 1; Fig. 5 is a detail of a driving connection; and Figs. 6, 7, 8 and 9 are fragmentary perspective views illustrating the cycle of operations of the looper in conjunction with the needle.

The general construction of the chain stitch machine illustrated is familiar to those skilled in the art as a well known commercial device. It suffices here to generalize that the upper frame arm 10 carries a rigid presser foot 11 having a work opening 12 into which there works the plunger 13 suitably coördinated with the feed mechanism 14 and clamp element 15, all carried by the lower frame arm 16, the shaft for these work-handling and presenting parts receiving power through connections (not shown) from the main shaft 17 which extends through the upper arm and which also drives the needle bar 18, take-up 19, and looper mechanism 20. The needle bar 18 is pivoted on the upper arm with its axis paralleling the line of feed substantially in the vertical plane of the plunger, so that needle 18' works transversely to the line of

feed and, in this specific instance, at right angles thereto, directly over the plunger. The needle bar 18, in the particular construction shown, is driven by link 21 from crank pins 21' on a gear 22 the shaft 23 of which extends to the rear of the frame arm 10 to actuate the looper driving mechanism, this gear 22 in turn being driven by a gear 24 on the main shaft 17. As thus far described, the machine involves nothing novel *per se*.

The novel looper structure specifically shown includes a bar 30 having a rigid point 31, which bar is adjustably connected by a screw and slot arrangement 32 to the carrier 33, the bar 30 also carrying a pivoted spreader-arm member 34 with its point 34' movable relative to the main point 31, these connected parts constituting what we may term as a whole the movable unit of the looper. This looper unit is arranged in an upright position, presented approximately at right angles to the plane of the presser-foot, and receives bodily movement up and down, fore and aft (transversely to the line of needle travel) and from side to side (or in the direction of needle travel) all without change of its angle with respect to the presser foot. To this end the carrier 33 of the unit receives this up and down and side-wise movement from parallel cranks of equal length, and the unit receives its fore and aft movement as a sliding action parallel to the crank axes.

In the specific construction shown the aforesaid cross shaft 23 for driving the needle bar carries a balanced disk 35 at the rear of the machine which, through a roller 36 operating in slot 37 drives the pivoted lever 38 which, through gear segment 39, in turn drives the pinion 40 on shaft 41 from which motion is communicated to shaft 42 by reversing pinion 43 and pinion 44. The shafts 41 and 42 disposed in parallelism and actuated alike and equally are the shafts of the parallel crank system. The shaft 41 preferably extends through the hub of the needle bar 18 and gives the latter its bearings, as shown in Fig. 4, thus locating the principal crank of the looper system coaxially with the needle bar. Shafts 41 and 42 have corresponding heads 45 and 46 from which extend the parallel crank pins 47 and 48, the former affording a long bearing for the cylindrical hub 49 of looper carriage 33 and the crank 48 receiving an open guide-

yoke 50 of said carriage. It will be apparent that, in appropriately timed relation to the oscillations of the needle bar 18, the crank shafts 47 and 48 will be equally oscillated in like directions, so that the movable looper unit will be transported bodily, and without change of its angular position, from side to side and up and down.

The hub of the looper carriage carries a laterally extending headed pin 51 engaged by the slotted end 52 of an arm 53 that is vibrated fore and aft about a transverse pivot 54 by means of a cam 55 on the main shaft. The cam slot 56 receives the roller 57 on the crank arm 58 the long hub 59 of which receives ample bearing on the pivot pin 54 mounted in the frame. The lever arm 53 is preferably connected with this hub 59 by a pivot pin 60 transverse to the pin 54, these loose connections at both top and bottom of the arm 53 insuring its adequate freedom of movement both laterally and vertically with respect to the looper carriage, but maintaining an effective connection whereby the cam operated lever may slide the carriage fore and aft along its crank pin 47.

The precise structure of the looper point or points may be varied, and the particular spreading-point construction herein shown is not novel in this application. Suffice it here to say that the spreader point 34' is closed by spring 62 upon the main point 31 when the point structure enters the loop, above the needle, as shown in Fig. 9, and that the two points are separated when, as shown in Fig. 7, the needle enters the loop the tail 63 of the spreader point striking the cam 64 fast on the head of the machine to effect this action.

40 In the cycle of operation as shown in Figs. 6 to 9, when the needle is sufficiently retracted to throw out the loop, the parallel crank pins stand at their rightward limit of oscillation, positioning the looper unit in fore and aft register with the loop, and when the parts arrive in this position cam 55 on the main shaft operates lever 53 to advance the closed looper points so that they pass through the loop above the needle; then during the retraction of the needle the cam holds the looper carriage 33 forward while the crank pins oscillate to their leftward limit of movement, the loop thus being carried over the work as shown in Fig. 6 until the tail of the spreading looper-arm strikes its cam 64, whereupon the looper points spread as shown in Fig. 7, the main or rigid point 31 being depressed below the needle and the spreader point is held above the needle which meanwhile has passed its fully retracted position and has begun its next penetration stroke. As the needle sweeps through the open loop thus positioned, the cam on the main shaft operates lever 53 to retract the looper unit, sliding it aft on its crank pin

47 to the position shown in Fig. 8, in which aft position or zone it remains while the parallel crank pins convey the carrier sideways through its idle excursion over the work to the rightward end of the path of crank 70 oscillation, completing the cycle.

It will be observed that by the parallel-link effect, maintaining the looper unit always in the same angular position in its vertical and lateral movement, the crank pins travel through the full space that is traveled by the rigid looper point, and that all parts that would be subject to wear have large and adequate bearing surfaces, so that irregularities in looper movements due to initial or wear-engendered loosenesses of fit are minimized. Also it will be noted that all connections are of the simplest variety conducive to accuracy and low cost in production. It will be understood, however, 85 that in the broader aspects of our invention we do not limit it specifically to the illustrated construction shown, as many changes in detail may be made without departure from the spirit of our invention and within 90 the scope of the appended claims.

What we claim is:

1. The combination with a laterally reciprocating needle and means for presenting work thereto, of a looper comprising a movable unit having a looper-point, and means for moving said unit through a six-way path without changing the angle of said unit with respect to the plane of the work. 95

2. In a sewing machine, the combination 100 with a transversely reciprocating needle and means for presenting and feeding work with respect thereto, of a six-way looper comprising a movable unit having a looper-point, parallel equal crank members for 105 moving said unit bodily, without change of its angular position, up and down and transversely and means for moving said looper-point fore and aft across the path of needle traverse. 110

3. In a sewing machine, the combination with a transversely reciprocating needle and means for presenting and feeding work with respect thereto, of a six-way looper comprising a movable unit having a looper-point, 115 parallel equal crank members for moving said unit bodily, without change of its angular position, up and down and transversely and cam-actuated means for moving said looper-point fore and aft across the 120 path of needle traverse.

4. In a sewing machine, the combination with a transversely reciprocating needle and means for presenting and feeding work with respect thereto, of a six-way, chain-stitch 125 looper comprising a movable unit having a point, parallel equal crank members for moving said unit bodily, without change of its angular position, up and down and transversely, and means for moving said unit 130

bodily, without change of angle, fore and aft, to pass said point across the line of needle traverse.

5. In a sewing machine, the combination with a transversely reciprocating needle and means for presenting and feeding work with respect thereto, of a six-way, chain-stitch looper comprising a movable unit having a point, parallel equal crank members for moving said unit bodily, without change of 10 its angular position, up and down and transversely, and means for sliding said unit bodily, without change of angle, fore and aft, to pass said point across the line of 15 needle traverse.

6. In a sewing machine, a looper, providing a vertical looper bar having a point at its lower end, and means for bodily raising and lowering said looper bar, bodily displacing it laterally, and bodily displacing it fore and aft, said means maintaining unvaried the angular relation of the bar to the stationary portions of the machine.

7. In a looper mechanism for sewing machines, the combination with a frame of a looper unit having a point, a pair of parallel crank shafts carried by said frame having parallel similarly disposed pins of equal radius carrying and guiding said looper unit 30 in an arcuate path, and means for sliding said looper unit fore and aft with respect to the frame.

8. In a looper mechanism for sewing machines, the combination with a frame of a

looper unit having a point, a pair of parallel 35 crank shafts carried by said frame having parallel similarly disposed pins of equal radius carrying and guiding said looper unit in an arcuate path, and means for sliding said looper unit fore and aft with respect to the crank-shaft.

9. In a sewing machine looper mechanism, the combination of parallel cranks, means to operate them, a looper unit carried by and 40 slideable on said cranks, and including a 45 looper-point, and means for sliding said looper unit on said cranks.

10. In a sewing machine, a chain-stitch looper structure comprising a pair of parallel cranks, means to operate them, a looper carriage carried by and slideable on said cranks, a cam, a lever vibrated thereby, and 50 lost motion connections between said lever and looper carriage, for sliding the carriage with respect to the cranks without restricting 55 the displacement of the carriage by the cranks.

11. In a sewing machine looper, the combination of a looper carriage, a looper-point carried thereby, a crank pin carrying said 60 carriage, a second crank pin engaging and guiding said carriage, means for oscillating said crank pins, and means for moving the carriage in a direction axial with respect to one of said crank pins.
